ELECTRONIC VALVE AMPLIFIERS

Leslie Baden Mullett, Abingdon, England, assignor to The United Kingdom Atomic Energy Authority of Patents Branch, London, England

Application December 14, 1956, Serial No. 628,381

7 Claims. (Cl. 315—41)

This invention relates to electronic valve amplifiers and is particularly concerned with cathode structures for such amplifiers capable of producing a large current of stably bunched electrons.

The invention is based on the multipactor effect which is a phenomenon associated with surfaces whose secondary emission coefficient can (within a given primary energy range) be greater than one. Consider two parallel flat plates with an R.F. electric field normal to the plates; if an electron appears at the surface of one plate when the electric field is zero and it is then accelerated towards the other plate so as to arrive when the field is again zero, then the secondary electrons will in turn be accelerated back to the first plate. If the energy acquired is within the given range, further multiplied secondary emission takes place and the number of electrons builds up extremely rapidly. The phenomenon occurs over a range of phase angle (the angle during a cycle between zero field and the appearance of an electron at a surface) determined by the distance between the plates, the strength of the R.F. field and the secondary emission characteristics of the surfaces.

A multipactor oscillator making use of the above effect is described by Baker in U.S. Patent No. 2,674,694. A secondary emission electron multiplier utilizing the effect is also known, the electrons being collected by a probe entering the space between the plates.

According to the present invention in a cathode structure comprising two parallel plates adapted to support a R.F. electric field between them normal to their surfaces and to generate electrons by the multipactor effect, one of said plates is perforated such that an anode placed beyond the perforated plate collects those bunches of electrons which pass through the perforations.

An amplifier valve in accordance with the invention may comprise such a cathode structure, an associated anode structure, means for feeding R.F. power into the space between the plates (the multipactor space) and means for extracting R.F. power from the space between the cathode and anode structures (the electron interaction space).

The spaces into which the R.F. power is fed in and extracted may be in the form of resonant or travelling wave cavities.

In order that large quantities of R.F. power may be generated, the most advantageous construction is one allowing the inclusion of a large area of cathode. One such construction comprises a double coaxial line, the inner line providing the multipactor space and having a perforated outer conductor constituting the inner conductor of the outer line wherein electron interaction takes place, a D.C. voltage being applied to the outer sheath.

Another construction involving travelling wave cavities may comprise a double ridge-loaded waveguide, the septum being perforated and defining the multipactor space in relation to one of the ridges and the interaction space in relation to the other ridge.

2

Several embodiments of the invention will now be described by way of example with reference to the accompanying drawing wherein:

Fig. 1 is a diagrammatic section on a diameter of a valve in which resonant cavities provide the multipactor and interaction spaces.

Fig. 2 is a diagrammatic section along the axis of a valve in which a double coaxial line provides said spaces and

Fig. 3 is a diagram similar to Fig. 2 wherein a double rectangular waveguide provides said spaces.

Fig. 4 is a cross section of Fig. 3.

In Fig. 1 two E_{010} 10 cm. wavelength resonator cavities 1 and 2 are divided by a septum 3 having a central circular perforated area 4 overlying a cylindrical cathode post 5. The undersurface (in the diagram) of the perforated area 4 and the upper surface of the post 5 constitute cathodes and define the multipactor gap (space) and are of oxidised beryllium-copper to provide high secondary emission coefficients, i.e. >1.4 .

The input resonator 1 is designed to give only one mode of multipactor effect, the multipactor gap length being about .12 cm. so that an energy in the region of 500 volts is given to electrons having a half cycle transit time. The post 5 is 1 cm. diameter and the length of the resonator is 1.2 cm. The arrangement limits the multipactor effect to a region where the field is appreciably constant and provides a reasonable Q and feed system. The latter consists of a loop 6 extending from between the inner and outer conductors of a coaxial line 17.

The area 4 is perforated with closely spaced 2 mm. diam. holes to give a transmission ratio i.e. area of holes/total area of more than .5

The resonator 2 is provided with an anode 7 opposite 35 the perforated area 4 and with an output coupling 8 to a coaxial line 9.

In operation, on applying R.F. pulses to the input line 17, steady well-shaped electron current pulses equivalent to .25 amp./cm.² are obtained with a mean energy of 40 300-400 volts.

The current obtained for a given transmission ratio of the area 4 is found to be insensitive to contamination of the cathode surfaces or to the precise degree of vacuum.

The above described construction is most advantageous 45 for producing large powers on long wavelengths of the order of 150 cm. For example, at that wavelength a 50 kv. valve could have a diameter of 50-70 cm. and a total resonator length of about 7-8 cm., giving a current of the order of 200 amperes.

Referring to Fig. 2, the valve takes the form of a 50 length of double coaxial line. The cathode 5a is a cylindrical enlargement of the innermost conductor 10 and the perforated area 4a is formed in the outer conductor 3a of the inner coaxial line (the inner conductor 55 of the outer coaxial line). The multipactor space defined by the area 4a and the cathode 5a is thus annular. The outermost conductor 7b constitutes the anode and is supplied with a D.C. voltage. R.F. power is fed to the inner space and amplified R.F. power withdrawn from the outer space by loops as in the above described 60 embodiment.

In Figs. 3 and 4 is shown a double rectangular waveguide comprising channels 1a and 1b separated by a septum 4b and loaded by ridges 5b and 7b respectively.

The septum is perforated opposite the ridge 5b and defines the multipactor space therebetween. R.F. power is fed into channel 1a and withdrawn from channel 1b in any known manner. The ridge 7b constitutes the anode, to which a D.C. voltage is applied, and with the septum 70 defines the interaction space.

In order to eliminate large variations of power level along channels (due to attenuation in one case and power

gain in the other) feed back circuits (not shown) are provided on both channels.

In arriving at suitable parameters for such a valve two conditions for an electron in the interaction space are considered—one in which the transit time is very short and one in which it is comparable with half a cycle.

If the transit time is very short it can be shown that the electron velocity will remain at its value at injection and this low velocity combined with a short transit time calls for an extremely small interaction space.

It is, however, desirable to allow the electrons to speed up immediately after injection and to allow a considerable variation of R.F. field during the transit time.

It can be shown that there is an optimum transit time determined by the ratio E_0/E where E_0 is the maximum amplitude of the R.F. electric field and E is the D.C. field and occurs when the ratio is 1.38. Also the width l of the interaction space in cm. is related to E for a wavelength λ_0 by the expression $l/\lambda_0^2 = E \times 2.474 \times 10^{-8}$ cm.

Where λ_0 is in cm. and E in volts/cm. and if V is the applied D.C. voltage then—

$$(l/\lambda_0)^2 = V \times 2.474 \times 10^{-8}$$

Also, it is found that if the dimension l is scaled with wavelength, the applied voltage V , the quantity $E_0\lambda_0$ and hence the power flux W are all constants. The following table shows values of valve parameters based on these calculations, where W is the power flux in an H_{01} rectangular waveguide (channel 1b) of dimensions l and $.722 \lambda_0$ cm.

$E\lambda_0$ (kv.)	$E_0\lambda_0$ (kv.)	l/λ_0	V (kv.)	W (mw.)
500	690	.01237	6.365	2,045
636	877	.01573	10.0	4,201
750	1,035	.01856	13.92	6,904
1,000	1,380	.02474	24.74	16.36
1,422	1,962	.03517	50.0	47.01
2,011	2,775	.04974	100.0	133.0

The fraction of the circulating power which is available as power output is to some extent controlled by the allowable variation of field along the length of the valve, but is ultimately determined by the current since the D.C. will have been fixed.

For a given electron current the driving power is determined by the energy given to the electrons in multipactoring. If each electron acquires about 500 electron volts in a half cycle transit, the energy required to produce one electron from the perforated area $4b$ is of the order of 1000 e.v. The most optimistic power gain is therefore given numerically by the D.C. voltage applied to the valve in kv.

I claim:

1. An electronic valve amplifier comprising a cathode structure including two parallel plates adapted to support a R.F. electric field between them and to generate

electrons by the multipactor effect, one of said plates being perforated, an anode placed beyond the perforated plate to collect those bunches of electrons which pass through the perforations, means for feeding R.F. power into the multipactor space between the plates and means for extracting R.F. power from the electron interaction space between the cathode and anode structures.

2. An electronic valve amplifier as claimed in claim 1 comprising a double coaxial line, the inner line providing the multipactor space and having a perforated outer conductor constituting the inner conductor of the outer line wherein electron interaction takes place.

3. An electronic valve amplifier as claimed in claim 1 comprising a double ridge-loaded waveguide, the septum being perforated and defining the multipactor space in relation to one of the ridges and the interaction space in relation to the other ridge.

4. An electronic valve amplifier as claimed in claim 1 wherein said multipactor and electron interaction spaces are resonant cavities.

5. An amplifier comprising in combination a cathode structure consisting of two parallel spaced members defining a multipactor space, one said member being perforated, an anode structure spaced from the said cathode and defining therewith an electron interaction space, means including a resonator cavity for feeding R.F. power into the multipactor space, and means including a second resonator cavity for deriving R.F. power at a higher level from the electron interaction space, the facing surfaces of the said two parallel spaced members having secondary electron emission co-efficients greater than 1.4.

6. The invention as set forth in claim 5 wherein the said members are planar.

7. An electron discharge device comprising three elongated cylindrical conductors arranged in coaxial relationship, the middle conductor being spaced from the inner and the outer conductors, a portion of the inner conductor being of larger diameter than the remainder thereof and defining together with the opposed surface of the middle conductor a two element cathode structure, the said opposed surface being perforated, an anode structure comprising the portion of the outer conductor opposed to the said portion of the inner conductor, means to feed R.F. power into the spacing between the cathode elements, and means to derive R.F. power at a higher level from the spacing between the outer cathode element and the anode.
